TRIMMING MECHANISM

George T. Koch, Detroit, Mich., assignor to The Murray Corporation of America, Detroit, Mich., a corporation of Delaware

Application March 21, 1938, Serial No. 197,206

1 Claim. (Cl. 164—29)

The present invention relates to mechanism for trimming the margins of sheet metal stampings.

It is relatively common practice, particularly in the manufacture of automobile bodies, fenders, etc., to form by sheet metal drawing operations large complex stampings. In order to perform the drawing operation it is necessary to clamp the edges of the sheet of metal with the result that the clamping dies of the drawing press form flanges on the stamping which, with any excess material that may be present, must be trimmed off the stamping in a subsequent operation. Stampings are frequently formed with marginal portions at or near a right angle with respect to the main or center body of the stamping, and in such cases trimming cutters which operate on these marginal portions must operate in a plane substantially parallel to the main body of the stamping. This requirement presents serious obstacles to the design and construction of a suitable trimming mechanism, particularly as is often the case if the stamping must also be trimmed at some point on the main body portion by cutters operating perpendicular thereto. In that case certain of the trimming cutters must operate in one plane, and the remainder of the cutters must operate in a plane at right angles thereto in order to effect a complete trimming operation.

In the patent to Groehm No. 1,809,843, June 16, 1931, there is shown a trimming mechanism of the type which has been used in the past for performing trimming operations in two planes at right angles to each other; but this form of mechanism has a number of serious disadvantages among which is the fact that the horizontal operating cutters are positioned outside the confines of the stamping thus necessitating the use of a press of larger size than would be required to accommodate the stamping itself. In addition, in the Groehm mechanism the outer horizontally movable cutters are so arranged that they block access to the trimmed scrap and interfere with its removal from the mechanism.

It is one object of the present invention to provide a trimming die or mechanism of the type mentioned which is exceedingly compact, and which therefore can be used on smaller presses than can prior devices of the same class.

Another object of the invention is to provide a trimming mechanism of the type mentioned in which the strips of scrap metal trimmed by the mechanism are accessible to the operator for ready removal from the mechanism.

Another object of the invention is to provide a mechanism of the type mentioned adapted to trim entirely around the periphery of a sheet metal stamping in a single operation.

Other objects of the invention which include the provision of an improved arrangement of

cutters, and an improved and simplified arrangement of parts, will become apparent from the following specification and the accompanying drawings.

In the drawings,

Fig. 1 is a side elevation of the trimming mechanism showing portions upon the press upon which it is installed.

Fig. 2 is a fragmentary plan view taken on the line 2—2 of Fig. 1, showing one of the upper cutters at the forward corners of the machine.

Fig. 3 is an end elevation of the pair of cutters at one front corner of the machine.

Fig. 4 is a plan view of the mechanism having parts broken away to show the interior construction.

Fig. 5 is a longitudinal section view taken on the line 5—5 of Fig. 4.

Fig. 6 is a fragmentary section view taken on the line 6—6 of Fig. 4.

Fig. 7 is a section view taken on the line 7—7 of Fig. 4 with the parts in partly open condition.

Fig. 8 is a section taken on the line 7—7 of Fig. 4 with the parts in closed position.

Fig. 9 is a section taken on the line 9—9 of Fig. 4.

Fig. 10 is a section taken on the line 10—10 of Fig. 4.

Fig. 11 is a perspective view of the sheet metal stamping which the trim mechanism shown in Figs. 1—10 is designed to operate upon.

Fig. 12 shows the sheet metal stamping after it has been trimmed.

Fig. 13 is a fragmentary sectional view taken on the line 13—13 of Fig. 11.

In Fig. 11 of the drawings there is shown an automobile body panel A in the condition in which it leaves the drawing die. The panel A, shown for the purpose of illustration, is a one-piece top and rear quarter panel for a coupé, but it will be understood that the present invention is applicable to similar panels for other automobile body stampings, and that if desired the panel may also be extended at the front to include the front pillar elements or at the rear to include the complete rear back of the automobile body, or both. The invention is also applicable to other sheet metal stampings such as automobile fenders and the like.

The drawing die, not shown, is provided with elements for gripping the periphery of the panel prior to the drawing operation, and these gripping elements form a flange B having grooves C therein. It is necessary following the drawing operation to trim off the flange B and to trim the panel to the desired shape, and the machine shown in the present application is designed to so trim this panel in a single operation to the condition shown in Fig. 12.

It has been recognized that in trimming panels

of the type here involved it is highly desirable, if not essential, to perform some of the trimming operations by shearing in a horizontal plane, and others by shearing in a vertical plane depending upon whether or not the panel at the point under construction extends nearer to the vertical or nearer to the horizontal. Where the margin of the panel at any given point extends in a generally vertical plane horizontal shearing is necessary to avoid subsequent finishing operations or increased die cost. For example, in Fig. 13 there is shown a section of the panel A taken on the line 13—13 of Fig. 12 in which the desired trim line is indicated by the dotted line X. At this point on the panel, if it were necessary to shear in a vertical direction it would be necessary to provide on the panel a clamping flange D shown in dotted lines, and then shear vertically on the line X'. Thereafter the remaining horizontal projecting flange portion would have to be rolled until its edge fell on the line X. This rolling operation is expensive and troublesome. Moreover, difficulties may be encountered in providing a clamping flange at the point D due to the well known requirement that the plane of the peripheral gripping surfaces on the drawing die must be of such configuration that a flat sheet of flexible material will conform thereto without wrinkling or stretching. This requirement frequently prevents the formation of a clamping flange at or near the desired trim line. If the holding flange cannot be located at the proper point with respect to the trim line, then, if vertical shearing is to be used it is necessary to so shape the drawing die that it will form a special horizontal trim flange in a different plane from the holding flange; obviously an expensive expedient. The situation is just the reverse where, as at the rear of the panel A, the panel extends in a substantially horizontal plane. There vertical shearing must be resorted to.

In the particular machine by which the present invention is exemplified suitable shearing cutters are provided for trimming the entire periphery of the panel A along the trim line X in a single operation, and at the same time cut the peripheral severed portion at the four corners on lines Y. The shearing cutters which operate on the trim line fall into groups, some operating in a horizontal plane and others operating in a vertical plane. At each side of the panel along those portions of the trim line indicated E in Fig. 11, the shearing cutters operate on a horizontal plane. The same is true of the shearing cutters which operate along that portion of the trim line at the front of the panel which is indicated G in Fig. 11. All of the remaining shearing cutters, namely those which operate along the rear of the panel at H and the front corners at K, operate in a vertical plane. It will be understood that the particular arrangement of vertical and horizontal shearing areas is controlled by the shape of the panel and the contour of the trim line, and will be different for panels of different shapes and contours.

In Figs. 1 to 10 of the drawings there is shown the details of a machine adapted to perform the trimming operations above described. The trimming mechanism itself is mounted in a conventional power press having a movable upper press head 1, and a stationary bed 2 indicated fragmentarily in Figs. 1 and 5. Secured in any desired manner to the movable press head 1 is an upper die member indicated generally at 3. A lower die member indicated generally at 4 is

mounted for vertical sliding movement with respect to the bed 2 on guide pillars 6 shown best in Figs. 1, 4 and 7, which are fixedly mounted in a base plate 8 that is secured in any desired manner on bed 2. A plurality of springs 10 are positioned between the base plate 8 and the lower die 4, and exert a constant upward force tending to maintain the die 4 in elevated position with respect to the base plate. The lower die 4 is also constantly urged upward by a plurality of pins 11 which project through suitable openings in the bed plate 2 and base plate 8, and engage the under side of the lower die 4. Pins 11 are forced upward by a head 12 on a pneumatic cylinder 13 which is connected to a surge tank in the usual manner, not shown. The pins 11 and the pneumatic cylinder operate as a pneumatic spring which aids spring 10, and together they normally support the lower die 4 in the elevated position shown in Fig. 7. Suitable cap screws and associated sleeves 14 limit upward movement of the lower die to the position there shown.

The upper die 3 is provided with four downward projections 15, one at each corner, and the projections 15 have suitable guiding bores for receiving the upper ends of pillars 6, with the result that the upper die is guided with respect to the lower die by means of the pillars 6. The bottom surfaces of the projections 15 are provided with wear pads 16 adapted to engage similar wear pads 17 carried by the lower die 4, as best shown in Figs. 7 and 8 to limit downward movement of the upper die with respect to the lower die, for a purpose hereinafter set forth. The lower die 4 at its ends, as best shown in Figs. 1, 4 and 5, is provided with upward projections 19 extending above the lower position of the projections 15 on the upper die, and wear plates 20 and 21 are provided upon the projection 19 and engage the sides of projections 15 to assist pillars 6 in guiding the die members 3 and 4 for movement relative to each other.

When the upper die 3 moves downwardly during the trimming operation, in the manner hereinafter described in detail, the abutment wear plates 16 and 17 on projections 15 and lower die 4 respectively engage, and the lower die 4 is forced downwardly by the upper die against the action of springs 10 and pins 11. The lower die is guided during its vertical movement relative to the base plate 8 by pillars 6 previously described, and also by wear plates 22 and 24 mounted on projections 26 on the ends of the base plate 8, as best shown in Figs. 5 and 8. It will be noted that the projections 26 and the wear plates 22 and 24 mounted thereon project upwardly into suitable slots in the ends of the lower die 4.

The upper die 3 is provided adjacent its margins with downwardly extending end webs 30 and side webs 32 defining a continuous flange having its inner edge of substantially the same configuration as the horizontal projection of the trim line X on panel A. The webs 32 at the sides of the die connect projections 15, while webs 30 extend between webs 32 somewhat inwardly of the projections 15. Fixedly secured to the lower edges of webs 30 and 32 are a plurality of shearing cutters arranged in groups. At each side of the machine a plurality of shearing cutters 34 are secured by cap screws 35 in suitable recesses in a tool holding block 36, which in turn is secured in any suitable manner to the bottom edge of the web 32 at that side of

the machine. The block 36 is so shaped that the cutters 34 may be formed of uniform thickness, and have their lower or cutting edge conform to the horizontal projection of the trim line at the side of the panel. The two groups of cutters 34 have cutting edges at the inner side of the surfaces, and are adapted to cooperate with horizontally movable shearing cutters hereinafter described.

Another series of cutters 38 at the front of the panel are secured by cap screws 39 to a tool holding block 40, which in turn is secured to the adjacent end web 30 in any desired manner. (See Figs. 4, 5 and 9.) Cutters 38 are similar to cutters 34 previously described, and also cooperate with horizontally movable shearing cutters hereinafter described.

At each front corner of the upper die 3 at the intersection of webs 30 and 32 there is provided a cutter 42, best shown in Figs. 1, 2, 3, 4 and 9, comprising a downwardly extending flange 43 having a cutting edge 44 adapted to cooperate upon vertical movement with a cutter mounted on the lower die to trim the corner portion K of the trim line X. Cutter 42 also has a downwardly extended flange 46 having an edge 47 adapted to shear the peripheral holding flange of the panel along one of the lines Y of Fig. 11 to cut the scrap into strips, thus facilitating its removal from the mechanism.

At the rear web 30, and along the rear portions of the side webs 32 there is provided a continuous line of cutters 50, the lower edges of which are adapted upon vertical movement to cooperate with cutters mounted on the lower die 4 to shear the panel vertically along the portion H of the trim line X in Fig. 11. The cutters 50 at the rear corners are similar to cutters 42 previously described, being provided with diagonally extending cutting flanges 52 for splitting the peripheral flange B at the panel along the lines Y in Fig. 11. Cutters 50 are secured by cap screws to a U-shaped tool holding block 51 carried in any suitable manner on the rear web 30 and the rear ends of webs 32.

The cutters 34, 38, 42 and 50, all of which are fixedly secured to the upper die, have contiguous cutting edges forming in effect a continuous cutting edge entirely around the trim line X. In addition the upper die is provided with cutting blades 46 and 52 extending diagonally outwardly along the lines Y in Fig. 12 for severing the scrap into strips.

As best shown in Figs. 5 to 10 inclusive, the upper die 3 is provided with a presser member 60 positioned within the webs 30 and 32, and provided with a downwardly extending peripheral flange 61 having its bottom edge shaped to engage and fit panel A inwardly of the trim line. The outer surface of the flange 61 has a guiding engagement with blocks 36, 40 and 51, and is flush with the inner faces of cutters 42 and 50. The presser member 60 is vertically slidable with respect to the upper die 3 on studs 64, having sleeves 65 mounted thereon. The sleeves 65 are suitably flanged to limit downward movement of the presser member with respect to the upper die at the point shown in Fig. 7. A plurality of coil springs 66 between the upper die and the presser member 60 normally constantly urge the presser member downwardly with respect to the die. These are four springs 66, and four studs and sleeves 64 and 65, one at each corner of the presser member, as best indicated in Figs. 4 and 5.

The lower die 4 is formed as a heavy casting

having an inner vertical wall 70 providing a central opening which is generally T-shaped in plan. The head of the T extends from side to side at the forward end of the die in the plane of the left hand side of the section shown in Fig. 9. The wall 70 is provided at its top and bottom edges with outwardly extending parallel flanges 72 and 74 which form the top and bottom surfaces of the lower die; and these flanges are reinforced by a plurality of connecting webs 76 connecting outwardly from the wall 70. Additional reinforcing webs 78 are provided between the flanges 72 and 74 at the ends of the die. The lower die casting also includes a pair of parallel cross members 80 and 82 extending between walls 70 across the top of the T opening at the stem of the T, as best shown in Figs. 4, 5 and 10.

A work supporting member 86 is mounted on the die 4 by means of three centrally positioned legs 88, 89 and 90. Legs 88 and 89 seat upon cross members 80 and 82 respectively, and leg 90 seats on the flange 72 at the rear of the die, as best shown in Fig. 5. Longitudinally aligned keys 91, 92 and 93 shown in Fig. 5 are secured to the lower die by means of slots and cap screws and fit in aligned slots on the legs 88, 89 and 90 respectively, to properly locate the work support 86 transversely with respect to the lower die 4. A pair of aligned transverse keys 92 are similarly secured to cross member 80, and engage in a slot in the leg 88 of the work support 86 for positioning the work support longitudinally on die 4, as best shown in Figs. 4, 5 and 10. The periphery of the work support is shaped to conform to the panel A throughout the areas E and G of Fig. 12, as best shown in Figs. 5, 7, 8, 9 and 10, and in these areas engages the panel on the under side of the area engaged by plate 61 of the presser member. At the rear of the machine the work support 86 terminates on a line intersecting the junctions of areas E with area H, as best shown in Fig. 5. A plurality of stud bolts 94, one of which is shown in Fig. 5, are provided for securing the work support 86 on the lower die. A tool supporting block 96, shown in Figs. 4, 5 and 6, is secured by cap screws to the rear flange 72 of the lower die and carries a plurality of shearing cutters 98 adapted to cooperate with the cutters 50 to shear the panel A vertically along that portion of the trim line indicated G in Fig. 11. A pair of scrap cutters 100 are secured to flange 72, and cooperate with cutters 52 to sever the trimmed material along the rear lines Y of Fig. 11.

At the forward corners of the lower die are secured a pair of cutters indicated generally at 102 each having a cutting member 104 adapted to cooperate with the inner side of flange 43 of the associate cutter member 42 on the upper die 3 to trim the panel A at one of the corner areas K. Cutters 102 are also each provided with a diagonally extending cutter 106 adapted to cooperate with the scrap cutter 46 on the upper die to sever the trim material along the lines Y at the front of the panel.

All of the cutters 98, 100, 104 and 106 are fixedly secured to the lower die, and they are adapted to cooperate with the cutters 50, 52, 43 and 46 respectively, when the die members 3 and 4 approach each other to vertically shear the panel A along the trim line at the areas K and H of Fig. 11, and also to sever the trimmed material at the lines Y into four easily removable scrap strips. Coil springs 10 and the pneumati-

cally spring urged pins 11 prevent any substantial downward movement of the lower die 4 until after the vertical shearing of areas K and H is completed. The parts are so arranged that immediately upon completion of this vertical shearing operation wear pads 16 and 17 on the dies 3 and 4, respectively, contact each other, and thereafter any further downward movement of the upper die causes a similar downward movement of the lower die 4 against springs 10 and pins 11. This downward movement of the lower die operates means hereinafter described to effect horizontal shearing operations.

At each side of the machine and resting on lower die 4 is a tool holding block 110 which extends the full length of the horizontal shearing area E of the trim line, as best shown in Fig. 4. The blocks 110 rest upon a plurality of bronze wear pads 112 which seat in suitable recesses in flange 72 of die 4; and the under side of each block 110 is provided with grooves adapted to receive the key member 92, as shown in Fig. 10. Each block 110 is provided on its top surface with recesses 114, 115 and 116 in which are received bronze wear pads 111, 118 and 119 respectively, which are secured to the under side of the work support 86. The bronze wear pads and key 92 guide the blocks 110 for translatory sliding movement on lower die 4. Blocks 110 are normally urged inwardly by means of a plurality of coil springs 122, which engage between the outer sides of each block 110 and a block 124 which is secured to the edge of flange 72 by means of cap screws 125. A cover plate 126 encloses the springs 122.

A plurality of shearing cutters 128 are secured to the outer sides of block 110 and are adapted on outward movement of the blocks 110, after wear plates 16 and 17 have contacted to cooperate with the cutters 34 on the upper die, to shear the panel horizontally along the sections E of the trim line. The inner side of each of the blocks 110 is provided with three inclined cam faces 129, 130 and 131 adapted to cooperate with suitable cams hereinafter described for forcing the blocks outwardly against the springs 122 to effect the shearing operation. A tool holding block 136 is slidably mounted on flange 72 at the forward end of the lower die for translatory movement longitudinally of the die. A key 138 shown in dotted lines in Fig. 9 fits in suitable grooves in the blocks 136 and flange 72 to maintain the block in proper alignment. Bronze wear pads 140 between the block 136 and flange 72, and pads 142 between the block and the work support 86 guide and support the sliding block 136. A plurality of shearing cutters 143 are mounted on block 136 and cooperate with cutters 38 on the upper die to shear the panel horizontally along section G of the trim line after pads 16 and 17 contact and the block 136 is moved outwardly. Springs 144, similar to springs 122 in construction and arrangement normally urge the blocks 136 inwardly, while inclined cam faces 146 on block 136 cooperate with cams hereinafter described for moving said block outwardly to effect the shearing operation.

The means for effecting outward movement of the blocks 110 and block 136 carrying the horizontally movable cutters comprises a stationary casting indicated generally at 150 in Figs. 5, 7, 9 and 10. This casting is generally I-shaped in transverse cross section as best shown in Figs. 7, 8 and 9, although at one end, as shown in Fig. 9, the flanges are extended outwardly at 151 so that

in plan view the casting is generally T-shaped with the head at the T at the forward end of the machine. This T-shaped casting is positioned within the confines of the T-shaped opening defined by wall 70 of the lower die, and it is fixedly secured to the stationary base plate 8 by means of cap screws 152. The casting 150 is provided with suitable cut-away portions 153 to provide clearance for the cross members 80 and 82 of the lower die 4, as best shown in Figs. 5 and 10. The head or upper flange 154 of the I section casting 150 is connected with the base 155 by three transverse reinforcing webs 156, 157 and 158. The head 154 is provided at each side with three inclined bronze wear pads 160, 161, and 162 in alignment with the transverse webs 156, 157 and 158 respectively, and adapted to engage the inclined faces 129, 130 and 131 on the adjacent block 110 to force the same outwardly when the lower die moves downwardly with respect to the base plate 8. At the front end of the machine the transversely extended head 154 of the I casting is also provided at its forward side with a pair of inclined wear pads 166 adapted to engage the inclined surfaces 146 on block 136 to move the same outwardly and effect the shearing operation when the lower die moves towards the base plate. The trim mechanism operates in the following manner. At the beginning of the trimming operation the press heads 1 and 2 are separated to an even greater extent than is indicated in Fig. 7, thus making it possible to place an untrimmed panel A in the mechanism until it rests upon the work support 86, and is properly located thereon. At this point in the cycle of operation the lower die and remaining parts of the mechanism are in the position shown in Fig. 7. The press is then started, and as the upper die 3 moves downwardly the flange 61 on presser member 60 engages the panel and clamps it against the work support 86, and also against the top edge of the stationary vertical shearing cutters 98 and 104 in the manner shown in Figs. 5 and 6. Upon further downward movement of the upper die 3, springs 66 which normally urge the presser member 60 downwardly will be compressed due to the fact that they are insufficient in strength to overcome the force exerted by springs 10 and pins 11 on the lower die 4. Accordingly, the upper die 3 will continue to move downwardly while the presser member remains substantially stationary with the result that the panel will be sheared along the sections H and K by the vertical shearing knives 50-98 and 43-104 carried by the upper and lower die members respectively. Simultaneously with the above described shearing action, the scrap cutters 46-106 and 52-100 will sever the scrap strips along the lines Y in Fig. 12. Upon completion of this shearing operation wear pads 16 and 17 on the upper and lower dies respectively engage each other, thus limiting further downward movement of the upper die relative to the lower die at the point shown in Figs. 1, 5, 6, 8, 9 and 10, in which position the cutting edges on the horizontal movable cutters 34 and 128 which cooperate to shear the area E on the panel and cutters 38 and 143 which cooperate to shear the area G on the panel are in the same plane and therefore in proper juxtaposition to perform the shearing operation. Thereafter as the upper die 3 continues to move downwardly any further movement of the upper die towards the lower die 4 is impossible so the two dies 3 and 4 move downwardly as a unit against the action of springs 10 and pins 11. The downward

movement of die 4 from the position shown in Fig. 7 to the position shown in Figs. 1, 5, 6, 8, 9 and 10 carries the two holding blocks 110 and block 136 downwardly with respect to the stationary cam plates 160, 161, 162 and 166 on casting 150 with the result that the cam plates force blocks 110 and 136 outwardly. The cutters 128 and 143 on blocks 110 and 136 respectively cooperate with the stationary cutters 34 and 38 respectively during this downward movement to shear the plate along those sections of the trim line indicated E and G in Fig. 11, thus completing the trimming operation. The press is then reversed, and the upper die elevated to sufficient height to permit removal of the trimmed panel.

It will be noted that due to the fact that the stationary horizontal cutters 34 and 38 are carried by the upper die, while the movable horizontal cutters 128 and 143 are carried by the lower die and move outwardly to effect the shearing operation that the scrap strip is readily accessible for removal from the mechanism. In fact, it is possible to grasp the scrap strip prior to the shearing operation and hold onto it during the trimming operation until it is completely severed, and then remove it from the machine without any danger of injury. This is true of each of the four scrap strips that are formed during the trimming operation. It will be noted also that since the movable horizontal cutters are positioned beneath the work support 86, and move outwardly to effect the shearing operation that the mechanism is much more compact than is possible in a mechanism having inwardly moving horizontal shearing cutters, with the result that the mechanism can be operated by a much smaller press than the type of trimming mechanism having inwardly moving shearing cutters. This is a very important advantage in view of the fact that trimming mechanisms here involved must, as a practical matter, be installed upon conventional power presses which in general increase in power and weight in proportion to the size of the die area provided thereon. No great power is required to trim a stamping of the type under consideration, so the size of the press is controlled entirely by the size of the mechanism used, and it is highly desirable to use as small a power press as possible in order to avoid the expense.

It will be understood that the particular arrangement of cutters described above is governed to a large extent by the shape and nature of the stamping for which the mechanism is designed, but that the principles and advantages of the invention are fully applicable to other detailed arrangements. For example, in some cases it may be advisable or necessary to eliminate one or more, or all of the vertical operating shearing cutters and replace them by horizontally moving cutters, and this may be done without departing from the spirit of the invention. If the vertical cutters 42 and 102 on the forward corners of the mechanism are eliminated they may be replaced by similarly horizontally moving cutters carried by extensions of blocks 110 and 136. In such an event it will be necessary to overlap the blocks 110 and 136 at their corners, but otherwise the arrangement would be substantially that shown.

While it is preferred to have the horizontally

movable cutters carried by the lower die, as shown, it will be observed that so far as compactness of the mechanism as a whole and accessibility of the scrap are concerned they could be carried by the upper die and cooperate with cutters on the lower die. In this event the panel A would be placed in the machine upside down. Such an arrangement would be the equivalent of turning the entire mechanism upside down.

Furthermore, while it is preferred to have the horizontally movable cutters move outwardly to perform the shearing operation, since such an arrangement results in a more compact mechanism, nevertheless it is possible to have the horizontal cutters move inwardly and still have the scrap strips accessible provided the horizontally movable cutter is carried by the upper die when the panel flanges are turned downwardly, or by the lower die if the panel flanges project upwardly. In other words, scrap accessibility is achieved by securing the outermost cutter, whether movable or stationary, to the die member opposite the die member toward which the panel flange projects. Or as stated in the claim, the outermost cutter must be located at the extreme projection of its supporting means in the direction in which the panel edge to be trimmed thereby projects.

It is apparent that various changes in the construction and arrangement of the parts shown and described may be resorted to without departing from the spirit of the invention or the scope of the appended claim.

What I claim is:

35 In a trimming mechanism, an upper die, a base plate, a lower die intermediate the upper die and base plate, said dies being adapted to receive a work piece therebetween, and to move toward each other, a pair of shearing cutters 40 fixedly carried by the upper die, a shearing cutter fixed on the lower die and adapted upon movement of said dies toward each other to cooperate with one of said cutters on the upper die and thereby trim a portion of the work piece, 45 a second shearing cutter slidably mounted on the lower die for movement in a direction substantially perpendicular to the direction of relative movement between said dies and adapted on outward movement to cooperate with the other of 50 said cutters on the upper die when said dies are in a predetermined relative position to trim another portion of the work piece, a cam carried by the base plate and operable when said lower die is moved toward said base plate to force said 55 movable cutter on the lower die outwardly, resilient means for maintaining said lower die in elevated position with respect to said base plate, means for moving said upper die toward said lower die and base plate, and means for limiting 60 movement of said upper die toward said lower die upon completion of the operation of said shearing cutters on said first portion of the work piece and at the point at which said dies are in said predetermined position whereby upon further movement of said upper die said upper and lower dies will move as a unit toward said base plate against the force of said resilient means 65 and effect operation of said second shearing cutter by said cam.

GEORGE T. KOCH.
